RING SPINNING APPARATUS

Edmond R. J. Dufond, Sao Paulo, Brazil

Application August 7, 1947, Serial No. 767,105
In Brazil June 17, 1941

7 Claims. (Cl. 57—124)

1

It is an object of this invention to provide improved apparatus for ring spinning yarns and particularly to provide such apparatus so arranged as to have minimum wear of parts, maximum acceleration in starting up and which will be capable of handling every possible condition from maximum ballooning to maximum stretch. The above and other objects will be made clear from the following detailed description taken in connection with the annexed drawing in which

Fig. 1 is a vertical cross section of the apparatus as a whole, and

Fig. 2 is a section on the line 2—2 of Fig. 1.

In the prior art when a spindle or bobbin has been run on a ring spinning machine the traveller has had a simple mechanical bearing on a fixed portion of the machine. There has been a length of thread or yarn extending radially between the traveller and the bobbin and under a combination of centrifugal force and the sheer drag of the yarn, the traveller has been impelled to rotate with the spindle. This has presented difficulties in starting up, and has also made the weight or mass of the traveller a critical element in the performance of the apparatus as a whole. The present invention uses the rotation of the spindle or bobbin itself to apply accelerative force to the traveller so that no longer is dependence placed on the yarn alone. This arrangement largely negatives the effect on the spinning process of the weight or mass of the traveller which, in the case of this invention, for all practical purposes has zero mass. With this has been combined means for adjustably retarding the rate of rotation of the traveller, whereby providing, in effect, adjustable mass or weight.

In Fig. 1 there is shown a hollow casting 10, having a flange 12 secured to any fixed part of the machine frame 14 by means of bolts 16. Mounted on each end of the casting 10 are ball-bearings 18 in which is mounted a sleeve 20 held against axial shifting by a sleeve 22. The upper end of the sleeve 20 is a flange 24 and extending upwardly from the periphery of the flange 24 is an annulus 26. Immediately adjacent the flange 24 is formed a pulley 28 through which the annulus 26 is given rotary movement, as by a belt 29.

The interior of the sleeve 20 is axially grooved to receive splines 30 on a shaft 32 which receives rotary movement by means of the splines 30 and is given vertical movement by any suitable mechanism 33 connected to the lower end 34 of the shaft 32. A spindle or bobbin 36 is mounted at the upper end of the shaft 32.

2

Surrounding the upper end of the annulus 26 is a flange 38 defining an annular channel 40 which is partly filled with water, oil, glycerin, mercury or any other suitable liquid. The traveller 42 has an enlarged base 44 which supports the traveller by flotation in the liquid in the channel 40. Yarn 46 enters the traveller through a hole 48 and is wound up on the spindle 36. A guide 50 may be provided, optionally, to control the ballooning of the yarn 46.

An adjustable brake designated generally as 52 and best shown in Fig. 2 is provided to make contact with the traveller 42. This brake comprises opposed shoes 54 pivoted on fixed pivots 56 and having spring arms 58 connected to a threaded rod 60 to adjust the pressure of the shoes 54. The adjustment is made by means of a hand wheel 62.

Depending on the viscosity of the liquid in the channel 40 rotation of the channel will tend to drive the traveller 42 but there is ample slip in such drive to bring about a winding action of the yarn 46 on the spindle 36 and the amount of slip, hence the stretch and ballooning may be controlled by adjustment of the shoes 54.

When it is desired to use the principles of this invention in apparatus having its axis of rotation other than vertical, a ball bearing, or other anti-friction bearing, may be substituted for the fluid 30 44 and the fluid channel 40.

While there has been described in detail one specific embodiment of this invention, it is obvious that it can be given numerous mechanical forms. It is not, therefore, to be limited by the details herein disclosed, but only as set forth in subjoined claims which are to be broadly construed.

I claim:

1. In ring spinning apparatus a spindle and means for rotating said spindle, a traveller surrounding said spindle, means for producing relative reciprocating movement between said traveller and said spindle, driving means for rotating said traveller, and an anti-friction bearing supported by said driving means and supporting said traveler, said traveler receiving only so much energy from said driving means as is transmitted by and through said anti-friction bearing.

2. A device as set forth in claim 1 including adjustable means for retarding the rotation of the traveller.

3. A device as set forth in claim 1, in which said anti-friction bearing comprises a cup-like member connected to said spindle for rotation

therewith, a body of liquid within said cup-like member, and in which said traveller has a portion floatingly supported by said liquid.

4. In ring spinning apparatus, a spindle, means for imparting rotation to said spindle, a traveller ring surrounding said spindle, an annular cup containing a liquid secured about said spindle beneath said traveller ring, said ring floating freely upon said liquid and receiving rotational energy thereby from said spindle, and brake means for limiting the rotational speed of said ring.

5. In ring spinning apparatus, a support, a cylindrical member mounted upon said support for rotation thereon and having an upwardly open, annular cup adjacent one end thereof, means for driving said member, a spindle passing axially through said member and having a splined connection therewith, a body of liquid in said cup, a traveller ring surrounding said spindle and having a portion buoyantly supported by said liquid, and a brake mechanism engaging said ring to limit the speed thereof.

6. In ring spinning apparatus a spindle and

means for rotating said spindle, a traveler surrounding said spindle, means for producing relative reciprocating movement between said traveller and spindle; an anti-friction bearing supported by said spindle rotating means and supporting said traveler, said traveler being driven by said spindle rotating means through said anti-friction bearing and receiving only so much energy from said rotating means as is transmitted by and through said bearing.

7. A device as set forth in claim 6 including adjustable means for retarding the rotation of the traveler.
